UNITED STATES PATENT OFFICE.

JOHN SEM WOODAHL, OF GREAT FALLS, MONTANA.

ELEVATED ASH CARRIER.

Application filed November 18, 1926. Serial No. 149,035.

This invention relates to an elevated ash carrier.

The object of my invention is the construction of an apparatus which can easily handle or convey ashes from a building to a suitable depository in or near to an alley.

Another object of the invention is the construction of an elevated ash carrier that includes an efficient track structure upon which 10 travels a suitable ash box, and which ash box is manually operated upon said track structure for removing ashes from a building and depositing the same at a convenient place ready for the city ash collector to remove the same.

With the foregoing and other objects in view, my invention comprises certain novel constructions, combinations, and arrangements of parts as will be hereinafter fully 20 described, illustrated in the accompanying drawings, and more particularly pointed out in the appended claims.

In the drawings:

Figure 1 is a view in side elevation of an 25 apparatus constructed in accordance with the present invention.

Figure 2 is a sectional view taken on line 30 2—2, Figure 1, and looking in the direction of the arrows.

Figure 3 is an enlarged sectional view 35 taken on line 3—3, Figure 1, and looking in the direction of the arrows.

Figure 4 is an enlarged side view of one 40 of the auxiliary brackets.

Figure 5 is a sectional view taken on line 45 5—5, Figure 1, and looking in the direction of the arrows.

Figure 6 is a fragmentary, perspective 50 view of the inner end of the track structure.

Figure 7 is a perspective view of the ash 55 box or receptacle.

Figure 8 is an enlarged perspective view 60 of the primary bracket.

Figure 9 is a sectional view taken on line 65 9—9, Figure 8.

Fig. 10 is an enlarged sectional view taken 70 on line 10—10, Figure 8.

Referring to the drawings by numerals, 1 75 designates a building through an aperture 2 of which extends my ash carrier apparatus. The apparatus also extends into the shed 3, which shed is either adjoining an alley or built in the alley, so that the ash collector can have ready access thereto.

55 My apparatus comprises a track 4, preferably made up in sections, and this track is

supported by means of a primary bracket 5 and auxiliary brackets 6. The primary bracket 5 is preferably attached to a post or standard 7, and as shown in Figure 1, one 60 of the auxiliary brackets 6 is secured to post 8 and the other auxiliary bracket is fastened to the floor joist 9.

The primary bracket 5 comprises a vertical body 10 that terminates at its upper 65 end in pulley arm 11, on which arm 11 is an upstanding lug 12, to which is attached the cable supporting pulley 13. A bracket arm 14 is integral with the central part of the body 10 (Fig. 8), and this bracket arm extends outwardly from body 10 and has a head 15 formed on its outer end. This head 15 is T-shaped, and in the head is formed a notch or socket 16 (Fig. 9), which is to receive a horizontal "hook" or extension 17, as 75 shown in Figures 8 and 9. The contiguous ends of two sections of the track 4 meet at the bracket head 15 with these lateral extensions 17 serving to partly support the track 80 upon the head. To securely fasten the track upon the bracket, I use fastening means such as bolts 18. It will, therefore, be seen that each end of a section of the track is cut to provide said hooks or extensions 17 that engage the bracket, to partly support the 85 track upon the brackets, yet allow easy removal of the tracks from the brackets. The heads 19 of the auxiliary brackets 6 are similarly constructed as the head 15 of the primary bracket 5, and, therefore, it is not 90 necessary to repeat the description of this head 15 or 19.

The auxiliary bracket that is supported upon the post 8 extends upwardly, whereas the auxiliary bracket supported by the floor 95 joist 9 extends downwardly. Each auxiliary bracket 6 is provided with a bracket arm 20, upon the outer end of which is said head 19, and at the inner end of arm 20 is a vertically extending body 21 that is attached to the 100 post 8, or it may be attached to a floor joist 9.

The outer end of track 4 is secured by means of bolts 22 between two sheave plates 23 (Figs. 1 and 3). A sheave or pulley 24 105 is rotatably mounted on these plates, and around this pulley passes cable 25, which cable also travels over the pulley 13 on primary bracket 5. Depending from one of the plates 23 and positioned at right angles 110 thereto is striker plate 26, for the purpose hereinafter described.

The cable 25 passes also around drum 27 that is mounted upon a frame 28. By means of handle 29, the drum 27 is rotated. When the drum is rotated, movement will be imparted to cable 25. The lower run of the cable 25 normally rests in the V-shaped groove 30 of guide arm 31 of primary bracket 5. This guide arm 31 (Fig. 8) is provided with an upstanding portion 32, and this 10 guide arm and upstanding portion acts as a cable guide to keep the cable in proper position, and facilitate the operation of the apparatus. One end of cable 25 is suitably fastened to the ash box 33, at one end, and the other end of the cable is also fastened to the other end of the ash box, so that as the cable is "wound" around drum 27, the ash box will be pulled back and forth upon the track. When the ash box is in the shed 3, 15 by rotating drum 27, the ash box can be drawn through aperture 2 into the building to be loaded, and when loaded with ashes, or the like, by rotating the drum 27 in the opposite direction, the loaded ash box can 20 be caused to travel over the track to the shed 3.

The ash box 33 may be made completely of metal, or it may be constructed of wood and lined with sheet metal, such as tin and the like. It is provided with a hinged bottom 34, and this bottom is adapted to open automatically to dump the ashes in the ash storage portion 35 of shed 3. The hinged bottom 33, if in a closed position, will be 30 closed as the ash box passes out of shed 3 by said bottom striking or riding over the triangular bracket 36 fastened to the side of shed 3. On one end of ash box 33 is a bracket 37, on which is pivotally mounted catch 38. Catch 38 is integral with an outstanding weighted arm 39 and an upstanding trip arm 40. Trip arm 40 engages the striking plate 26, when the ash box has moved into the shed 3 to cause the catch 38 to disengage angle lug 41, attached to bottom 34, to allow the hinged bottom to move downwardly, whereby the ashes are dumped out of ash box 33. Then when the cable 25 draws the ash box back towards the building 1, the 40 open bottom 33 will ride over the triangular bracket 36, causing the bottom to close against the body of the ash box, whereby the catch 38 will move under angle lug 41, locking the bottom in a closed position upon the body of the ash box. The ash box is provided at its ends with brackets 42 that have horizontal lugs 43 at their upper ends. A hanger 44 is pivotally mounted by means of bolt 45 upon each lug 43. This hanger 50 (there are two of them employed) carries near its upper end a track wheel 46 that travels on track 4 (Fig. 2). A slight vertical play of wheel 46 upon track 4 is allowed, but the wheel will not jump off the track. This "swivel" mounting of hangers

44 upon brackets 42 allows a slight turning action of the ash box or receptacle on a curve, as might be desirable where the track was caused to turn in entering a building or the like. 70

The track 4 is supported at its inner end upon a bar 48 (Figs. 1 and 6) and this bar 48 is supported at its ends upon brackets 49, which brackets are attached to the frame 28 (Fig. 5). A stop plate 50 is fastened to the bar 49 contiguous to track 4, to prevent the track wheels 46 from moving off the track 4. 75

The ash or trash receptacle or box 33 can be easily drawn in and out of the shed or 80 building at the will of the operator, for the purpose of conveying rubbish or ashes from the building to the dump, which in the present instance is the ash storage compartment 85 of shed 3.

It is to be noted that I have produced a 90 novel track structure, involving the primary and auxiliary brackets supporting the track; that a load conveying receptacle travels upon the track, and manually operated means 95 is connected to the said load conveying receptacle for causing the same to travel over the track of said track structure.

While I have described the preferred embodiment of my invention and illustrated in 95 the same in the accompanying drawings, certain minor changes or alterations may appear to one skilled in the art to which this invention relates, during the extensive manufacture of the same, and I, therefore, reserve the right to make such changes or alterations as shall fairly fall within the scope of the appended claims. 100

What I claim is:

1. In an apparatus of the class described, 105 the combination of a primary bracket comprising a vertical body provided with an inclined pulley arm, said pulley arm terminating in an upstanding lug, a pulley supported by said lug, a bracket arm on said vertical body, said bracket arm provided with a head, said head provided with a notch, a track provided with side extensions or hooks, said hooks seated in said notch of said head, means extending through the 110 track and the head for positively fastening the same together, a guide arm under the track and integral with said vertical body, said guide arm provided under the track with a V-shaped groove, said guide arm 115 provided at its outer end with an upstanding portion, a receptacle travelling on said track, a cable having its upper run engaging said pulley and its lower run engaging said V-shaped groove, said cable being fastened at its ends to opposite ends of said receptacle, and means for hauling the cable back and forth for operating the receptacle upon said track. 125

2. In an apparatus of the class described, 130

the combination of a primary bracket provided with a bracket arm having a head, a sectional track having two lateral extensions in said head, means extending through the 5 track and the head for securing the same fixedly together, a movable receptacle supported upon said track, and means for pulling or causing the receptacle to travel back and forth on said track.

10 3. In an apparatus of the class described, the combination with brackets, of a track fastened to said brackets, a receptacle provided with brackets, swivelled hangers attached to said brackets, each hanger provided with a track wheel resting on said track, a cable having its ends fastened to the ends 15 of said receptacle, and means for causing said cable to travel and thereby cause said receptacle to pass back and forth on said 20 track.

4. In an apparatus of the class described, the combination of a track provided at one end with a striker plate, a receptacle provided with a hinged bottom mounted upon 25 said track, said bottom provided with a lug, said receptacle provided with a bracket, a catch pivotally mounted upon said bracket and normally engaging said lug for holding said bottom in a closed position, said 30 catch provided with a trip arm and with a weighted arm, said trip arm adapted to engage said striker plate for releasing the bottom, and means for causing the receptacle to move or travel upon the track.

35 5. In an apparatus of the class described, the combination of a track provided at one end with sheave plates, one of said sheave plates provided with a depending striker plate positioned at right angles to the 40 sheave plate, a receptacle provided with a hinged bottom travelling upon said track, a catch device provided with a trip arm adapted to engage said striker plate and release the catch device, said catch device normally holding said hinged bottom in a 45 closed position, and means for causing said receptacle to travel on said tracks.

6. In an apparatus of the class described, the combination of a frame, a drum mounted upon said frame, a track, a bar at one 50 end of said track, means fastening said bar

and track together, brackets fastened at the upper and lower ends of said bar, said brackets fastened also to said frame, a stop plate attached to said bar contiguous to said 55 track, a receptacle mounted upon said track, said stop plate adapted to prevent displacement of the receptacle off the track at one of the ends of the track, and a cable passing around said drum and attached at its 60 ends to said receptacle whereby when the drum is rotated, the receptacle will be caused to travel upon the track.

7. In an apparatus of the class described, the combination with a shed, of a triangular 65 bracket fastened to the side of said shed, a track above said triangular bracket and extending into said shed, a receptacle provided with a movable bottom adapted to be closed by said triangular bracket, said receptacle travelling upon said track in and out of said shed, and means for moving said receptacle back and forth upon said track.

8. In an apparatus of the class described, the combination of a shed provided with an 75 inclined bottom-closing bracket, a track extending into said shed above said bracket, a receptacle provided with a hinged bottom adapted to dump in said shed, means supporting said receptacle upon said track, said 80 bottom of the receptacle being moved to a closed position when passing over said inclined bottom-closing bracket, means on said receptacle for normally holding said bottom in a closed position, and means for causing 85 said receptacle to travel upon said track.

9. In an apparatus of the class described, the combination of a frame, a drum upon said frame, a track, a bar fastened to one end of said track, brackets fastened to said 90 frame and said bar for supporting one end of said track, means supporting the other end of said track, a receptacle travelling upon said track, a cable passing around said drum and attached at its ends to said receptacle, and means for rotating said drum and thereby actuating the cable and the receptacle.

In testimony whereof I hereunto affix my signature.

JOHN SEM WOODAHL.
